UNITED STATES PATENT OFFICE.

SEIZI TERADA, OF SEATTLE WASHINGTON.

FUSE-PLUG.

1,094,036.

Specification of Letters Patent.

Patented Apr. 21, 1914.

Application filed May 22, 1913. Serial No. 769,272.

To all whom it may concern:

Be it known that I, SEIZI TERADA, a subject of the Emperor of Japan, residing at Seattle, in the county of King and State of Washington, have invented certain new and useful Improvements in Fuse-Plugs, of which the following is a specification.

This invention relates to fuse-plugs.

The object is the improvement of devices 10 of this character wherein the various members are constructed and assembled to enable a new fuse to be conveniently substituted for one which has been burned out or "blown" without rendering the plug proper 15 unsuitable for further use.

With these ends in view, the invention consists in the novel construction and combination of parts, as hereinafter described and claimed.

20 In the accompanying drawings, Figure 1 is a side elevation of the improved fuse-plug. Fig. 2 is a longitudinal section of the same. Fig. 3 is a side elevation of the fusible element container shown detached.

25 The reference numeral 5, of the drawings, designates the plug-body constructed of porcelain or other suitable insulating material. The body has a cylindrical chamber 6 extending from its inner end to a recess 7 at 30 the outer end of greater diameter than the chamber and terminating at a shoulder 8. Surrounding the inner end of the body is a metal sleeve 9 which is formed with a screw-thread for engagement with a suitable 35 screw-socket and affords electrical connection with a contact provided in the socket.

11 represents an electrical conductor secured from one end to the sleeve 9 and thence extends through an aperture 12 provided 40 in the body and has its other end 13 turned or bent to lie against the shoulder 8. Inserted within the recess 7 is a circular plate 14 which is secured in juxtaposition with the end 13 of the above-mentioned conductor 45 and constitutes an extension thereof. Said plate is provided with a centrally disposed peephole 15 of less diameter than that of the chamber 6. Said plate is secured by applying cement of an insulating character 50 about the margin thereof, as indicated by 16 in Fig. 2.

17 represents the fusible element which is inclosed within a tube 18 of glass, porcelain or other suitable insulating material 55 and may be attached to the tube by bending the ends 19 over the ends of the tube, as

shown in Fig. 2. Fitted over the ends of said tube are metal caps 20 and 21 which serve as terminals for the fusible element. The cap 20 is provided with a sight aperture 22 and is closed by a sheet of mica 23 interposed between the cap and the adjacent end of the tube. At the outer end of the body is provided a sheet of mica 24 which is held in place by a flanged collar member 25. The fuse-container is constituted of the tube 18 and caps 20 and 21, and is of such length that when the cap 20 is against the plate 14 the other cap, 21, will protude from the inner end of the plug. 60 65 70

For operation, the container with an inclosed fuse is first introduced into the plug chamber 6, and then the plug is screwed into the usual electric-light socket with the result that the cap 21 and the sleeve 9 are 75 brought into electrical connection with the contacts provided in the socket. The contacts being thus connected, the gap therebetween is closed or bridged through the medium of the cap 21, the fuse 17, cap 20, plate 80 14, conductor 11 and sleeve 9.

When the fuse 17 is subjected to a current of greater amperage than the capacity of the fuse, the latter will be burnt out or destroyed to render it incapable of further 85 use. Such destruction of the fuse instantly produces an extremely great heat which usually results in the breaking of the tube 18 and the mutilation of the sheet of mica 23. The mica sheet 24 is, however, safeguarded 90 by means of the mica sheet 23 and the plate 14. After a fuse and its container have been rendered useless by the burning of the fuse, the plug is withdrawn from the socket, and a new container provided with a fuse 95 is substituted for those previously used, and the plug is restored to the socket.

The cost of the fuse and a container constructed in accordance with this invention is considerably less than the fusible plugs 100 such as have hitherto been generally used.

The plug proper may be repeatedly employed by replacing a ruined container and fuse by a new one, an operation which may be readily attained.

105 What I claim is:

1. A fuse-plug comprising a body provided with a metal external sleeve contact, a sheet of substantially transparent material extending across the outer end of the plug, a tube of non-conductive material inserted within the plug; metal ends for the tube; a

fusible element inclosed by the tube and connected with said metal ends, one of said ends being provided with a sight aperture and connected by a conductor with said sleeve contact, the other of said ends being disposed to serve as a contact complementary to the aforesaid contact; and a piece of mica extending across the sight aperture to protect said sheet from the effects of heat produced in the burning of the fusible element.

2. The combination with a chambered fuse-plug provided with an external sleeve contact and an electrical conductor extending from said contact to within the chamber of the plug, of a tube of non-conductive material inserted in the plug chamber, ends

of a conducting material for the tube, a fusible element inclosed by the tube and connected with both of said ends, one of said ends being provided with a sight aperture, and a sheet of transparent or semi-transparent material connected to the tube and extending across said sight aperture, one of said ends making contact with said conductor and the other end serving to afford a contact for the plug complementary to the aforesaid sleeve contact.

Signed at Seattle, Wash., this 12th day of May, 1913.

SEIZI TERADA.
